UNITED STATES PATENT OFFICE.

WILLIAM PAYNE BANCROFT, OF BOSTWICK, NEBRASKA.

LATCHING DEVICE.

1,107,569.

Specification of Letters Patent. Patented Aug. 18, 1914.

Application filed September 24, 1913. Serial No. 791,562.

To all whom it may concern:

Be it known that I, WILLIAM P. BANCROFT, a citizen of the United States, and a resident of Bostwick, in the county of Nuckolls and State of Nebraska, have invented a new and Improved Latching Device, of which the following is a full, clear, and exact description.

My invention, although capable of use as a latching device generally, is more particularly intended for use in connection with a swinging wringer support, to hold the latter in a given position.

It is a design of my invention to provide a latching device that will hold a wringer support or equivalent element tightly in the fastened position.

It is also a design of my invention to provide a latch improved in various particulars, with a view to promote economy of manufacture and simplicity of operation.

The invention will be particularly explained in the specific description following.

Reference is to be had to the accompanying drawings forming a part of this specification, in which similar characters of reference indicate corresponding parts in all the views.

Figure 1 is a perspective view of a latch embodying my invention, showing the same in connection with a wringer support; Fig. 2 is a perspective view, the wringer being omitted, and the wringer support being held in the latched position; and Fig. 3 is an end elevation.

In the drawings the invention is illustrated in connection with a swinging supporting bar 10, adapted to sustain a wringer A, the said bar being hinged to a washing machine or stationary tub B to swing over a receptacle C.

The latch bar 10, or any equivalent element to be fastened is provided with a lug 10^a adapted to be swung adjacent to a member B' supporting my improved latching device. Said latching device comprises a latch bar 11 having a hook 12 at one end thereof, thereby presenting a recess 13 to receive the lug 10^a. The latch bar is adapted to be moved upwardly and outwardly to clear the lug 10^a, in releasing the latter as hereinafter described. The inner wall 14 of the recess 13 is diagonal for the latch bar 55 to better clear the lug 10^a.

Adjacent to the front end or latching end

of the bar 11, a diagonal slot 15 is formed for receiving a relatively fixed pin 16, which in this instance is secured to the supporting member B'. A washer or washers 16^a on the outer end of the pin may be employed to prevent the displacement of the latch bar axially of the pin. That end of the latch bar opposite the hook 12 is connected with a lever 17 fulcrumed as at 18, to the fixed support and pivotally connected as at 19, to the latch bar. The relative arrangement of the lever and latch bar is such that the pivotal connection 19 of the latch bar in the latching position, will be dead-centered with the fulcrum 18, so that an outward pull on the lever by a force exerted against the supporting bar 10 or its equivalent will be resisted and an outward movement or releasing movement of the latch bar prevented. The latched position of the lever is indicated in Fig. 2, where it will be seen that the pivot 19 is on or slightly past a dead center, with the fulcrum 18; also in the latching position the handle 20 of the lever lies against the latch bar at the underside, the said handle constituting a lateral stop member, contact of which with the latch bar limits the movements of the parts. To throw the latch bar to the latching position, the lever is given a reverse movement from the position shown in Fig. 2 to that shown in Fig. 3.

The action of the lever on the latch bar is such that as the latch approaches the latched position it will be given more of a longitudinal movement than a vertical one, whereas the movement of the latch when near the unlatched position will be more nearly vertical, the purpose being to insure that in latching, the latch bar will first quickly be dropped downwardly over the lug 10^a of the member to be fastened, and will then be drawn rearwardly to draw the fastened member tightly against the support B', or equivalent element or structure. For the purpose mentioned a depression presenting a front wall 15 is formed complementary to the slot 15, at the lower end of the latter, and said wall approaches more nearly the vertical than the diagonal upper end 15^b of the front wall of the slot.

Having thus described my invention, I claim as new, and desire to secure by Letters Patent:

1. In a latching device, a latch bar formed with a hook at one end and with a diagonal slot adjacent to said hook, there being a de-

pression complementary to the slot near one end thereof, at the forward side, a relatively fixed pin extending into said slot, and a lever pivotally connected with the latch bar at the end opposite the hook, the lever and latch bar being movable to positions with the pivotal connection of the said bar approximately dead centered with the fulcrum.

2. In a latching device, a latch bar, a lever 10 pivotally connected with the bar near one end and fulcrumed on a relatively fixed support, the said bar having a hook formation at the end opposite the lever for latching engagement with the article to be latched, and 15 permanent supporting and guiding means for the latch bar between the hook formation thereon and the lever, said means comprising a diagonal slot in the said bar, additional to the hook formation, and a relatively fixed 20 pin extending into the said slot and afford-

ing support for the bar when the bar is not in latching engagement.

3. In a latching device, a latch bar formed with a hook at one end presenting a depression, the inner wall of said depression being 25 disposed diagonally to the hook, the latch bar furthermore having a diagonal slot approximately parallel with the said diagonal wall, a relatively fixed pin extending into said slot, and a lever pivotally connected 30 with the latch bar at the end opposite the hook.

In testimony whereof I have signed my name to this specification in the presence of two subscribing witnesses.

WILLIAM PAYNE BANCROFT.
